FOLDING SUPPORT FOR IRONING BOARDS
AND THE LIKEHarold Howe, New York, N. Y., assignor to Howe
Folding Furniture, Inc., New York, N. Y.

Application May 22, 1935, Serial No. 22,800

5 Claims. (Cl. 38—117)

My invention relates to a folding support for ironing boards and the like and has particular application to foldable articles such as ironing boards, tables, benches and the like, wherein a supporting surface is provided with foldable legs.

I have shown and will describe my invention as applied to an ironing board for which it has particular and peculiar merit and application, but it is to be understood at the outset that the device is equally applicable to other articles of furniture.

The primary object of my invention lies in the provision of a folding leg structure consisting of front and rear legs connected for synchronous folding against the underside of the supported surface, one of the legs being sectional to fold upon itself and extensible when unfolded.

An important object of my invention lies in the provision of a sectional folding leg connected by link means to the other leg or legs by means of which when the sectional leg is unfolded or extended, all the legs are synchronously unfolded to supporting position and when the sectional leg is folded upon itself, the other legs are simultaneously and synchronously folded to flat position on the underside of the supported surface.

More particularly my invention contemplates a sectional folding leg consisting of a pair of pivoted channel members, one adapted to be received within the other when in folded position, and connections between such channel sections and the other leg or legs whereby the same are operated simultaneously and synchronously.

Another object of my invention lies in the provision of a novel foot for one of the folding legs which foot serves the double useful purpose of a handle for manipulating the folding and unfolding of the legs, and for preventing creeping of the structure during use.

Still another object lies in the provision of a simple and effective locking means for the foldable leg sections whereby the same are held against collapse or folding during normal use.

Another object lies in the provision of a folding device which is simple, of few parts, and which provides a strong sturdy supporting means easily extended to operating position and as easily folded flat against the supported surface and within a minimum space.

Other objects and advantages will be apparent as the description proceeds, reference now being had to the figures of the accompanying drawings forming a part of this application and wherein like reference numerals indicate like parts.

In the drawings:

Figure 1 is a side view of an ironing board equipped with my improved folding mechanism, the same being shown in full lines in unfolded position, and in dotted lines in partly folded position. The board is shown in upside down position.

Figure 2 is a bottom plan view of the underside of the board with the legs folded thereagainst.

Figure 3 is a detail view of the sectional leg in extended or unfolded position.

Figure 4 is a detail sectional view of one end of the ironing board illustrating certain of the parts in folded position.

Figure 5 is a detail perspective view of the free end of the sectional leg showing the foot thereon.

Figure 6 is a detail view of a portion of the sectional leg, broken away at one point for clearness of illustration and showing the locking means for the sections.

Figure 7 is a diagrammatic view illustrating a slightly modified arrangement of the synchronizing links.

The reference character 1 refers to the supported surface or top, in this case, an ironing board, but for which might be readily substituted a table top, bench top or the like. Mounted upon the underside of this board 1 adjacent one end thereof is a flat plate 2 secured to the board as by the screws 3. Adjacent each end of the plate 2 are angular ears 4 which may be struck from the plate and bent at substantially right angles thereto and to which are pivoted, at one end, the rear legs 5. Pivot pins 6 pass through the ears 4 and through the legs 5 and are provided at each end with suitable heads or other means for suitably securing the legs against lateral movement but permitting free pivotal action thereof.

Also provided on the plate 2 are the ears 7 which may be likewise struck from the material of the plate and bent at substantially right angles thereto, to provide pivot means for braces 8 pivotally secured at one end to the ears 7 as by the pins 9 and at their opposite ends to the legs 5, by means of the pins 10 passing through such legs at points spaced from the pivoted ends thereof.

Also secured to the underside of the board 1 at a point substantially midway between the side edges thereof and substantially forwardly of the plate 2 is a second plate 11 suitably secured as by the screws 12. This plate 12 is provided with a pair of ears 13 formed on the plate in any suitable manner and extending at right angles thereto in parallel relation. A pivot pin 14 is journaled in the ears 13 and pivoted upon this pin 14 between the ears 13 is one end of a leg section 15.

preferably though not necessarily, of channel form. A spacing sleeve 16 may be provided between the flanges of the channel section 15 and surrounding the pivot pin 14 as shown clearly in Figure 3.

Pivoted to the opposite end of the leg section 15 is one end of a leg section 17 also of channel form and of a width to permit the sections to be folded together with the section 15 received within the channel section 17 as shown in Figure 2. The sections 15 and 17 are pivoted together by means of the pivot pin 18 passing through the flanges of the sections and it will be noted particularly with reference to Figures 1, 3 and 6, that the pivoted end of the section 17 extends beyond the pivot point for a substantial distance, such extending portion receiving and embracing the end of the section 15. This arrangement lends great strength and rigidity to the sectional leg when the sections are in their extended position.

The section 15 is provided with a slot 19 through which passes a headed pin 20 carried by a latch member 21 by means of which such latch member is slidably mounted longitudinally of the section 15. The latch also carries a second pin 22 passing through the slot 19 and extending for a distance into the channel of the section. The pins 20 and 22 serve to guide the latch 21 in its sliding movements and prevent turning thereof. Secured to the pin 22 is one end of a coil spring 23, the opposite end of which is secured to the pivot pin 18. Thus the latch 21 is normally urged to the left in Figure 6 or to latching position. The end of the latch is shouldered as at 24 to 35 overlap and engage the adjacent end of the section 17 when the sections are in their extended or unfolded position. When it is desired to fold the sections, it is necessary merely to slide the latch 21 to the right in Figure 6 until the shouldered end thereof releases the end of the section 17 which may then be rocked on the pivot 18. The spring 23 returns the latch to its normal position when released. When the section 17 is brought to its extended or unfolded position, the end thereof engages against the beveled end 25 of the latch, such engagement sliding the latch within the slot 19 until the end of the section 17 snaps past the shouldered end of the latch whereupon the same returns to the locking position shown in Figure 6.

Pivoted at one end to the rear legs 5 on the pivot pins thereof, are links 26, the opposite ends of which are pivoted as at 27 to the lower end of the section 17, the pivot pins 27 being suitably provided on the side flanges of the channel section 17.

Pivoted at one end to the rear legs 5 on the pivot pins 6 is a second pair of links 28, the opposite ends of which are pivoted to the section 17 as at 29, suitable pivot means being provided on the side flanges of the channel section 17. The pivots 29 are disposed at a point on the opposite side of the pivot 18 of the two sections from the pivot points 27 as shown clearly in Figures 1 and 3. It will be clear that with this arrangement of links when the section 17 is folded downwardly over the section 15, the links 26 and 28 will simultaneously and synchronously cause the rear legs 5 and the section 15 of the front leg to move downwardly to a position flat against the adjacent surface of the board 1. During this movement the position of the pivot points 27 and 29 will be reversed as shown clearly in Figures 1 and 2.

75 The diverging angle at which the rear legs 5

and the sectional front leg 15-17 extend from the board 1, permits this folding of the legs to a position flat against the surface of the board.

The free end of the section 17 is provided with a foot member 30 adapted to engage the floor 5 when the legs are unfolded and in such position is in the same plane as the ends of the rear legs 5 whereby the board 1 may be supported in a level horizontal position. This foot 30 may be of any desired material and as shown is formed 10 of metal in the nature of heavy wire or tubing secured at its ends to the end of the section 17 as at 31 and bent outwardly as at 32 to provide a wider engaging portion than the width of the section 17 and then bent or curled as at 33 in a 15 direction toward the opposite end of the board or toward the rear legs 5 as shown clearly in Figure 1. The bight of the foot 30 provides a convenient handle by means of which the section 17 may be grasped and moved to and from folded 20 position.

The bend or curl 33 of the foot 30 also serves the purpose of preventing the structure from creeping during use. When pressure is applied to the board 1 at a point over the foot 30 the force 25 is exerted downwardly against the foot and by virtue of the bend 33, rearwardly. If the bend of the foot were in the opposite direction, such downward pressure would exert itself not only downwardly but forwardly and the result would 30 be a creeping of the board during use. If Figure 1 of the drawings is observed in inverted position, this point will be especially clear.

In Figure 7 I have shown a slightly modified arrangement of the synchronizing links. In this 35 figure, the rear legs 5a are pivoted to the board 1a at 6a. Section 15a of the front leg is pivoted to the board at 14a. Section 17a of the front leg is pivoted to the section 15a at 18a. In this form the links 28a are pivoted at one end to 40 the rear legs 5a at the point 34 instead of at the pivot point of such legs, that is, spaced slightly from such pivot point. The opposite ends of the links 28a are pivoted directly to the pivot 18a. The links 26a are pivoted at one end to the rear 45 legs 5a at 10a and at their opposite ends to the section 17a at 21a, the same as in the form previously described.

In this modification, the elements bear the same numbers as the corresponding elements in 50 the previously described modification and the form of Figure 7 is, therefore, shown diagrammatically only. In this form the operation of the folding mechanism is identical with that previously described.

Referring now to Figure 4, it will be noted that the braces 8 are bent slightly as at 35 so as to accommodate the links 28 in the folded position.

It will be noted from the foregoing description 60 that with this folding mechanism all of the folding elements may be moved into a minimum space, all parts when folded lying within the plane of the board 1.

In operation it will be clear that with the parts 65 in the unfolded position shown in Figure 1 and the latch 21 moved out of locking position, the operator by grasping the foot 30 and rocking the section 17 on its pivot 18, will through the links 26 pull the rear legs 5 forwardly, the links 70 28 simultaneously serving to cause both sections 17 and 15 to move downwardly toward the surface of the board. This action is shown clearly in Figure 1. Obviously the reverse action will take place when the operator lifts upwardly on 75

the foot 30 with the parts in the folded position of Figure 2. Also, the operator may open or unfold the legs by pulling outwardly on either of the rear legs 5, the links or rods 26 and 28 serving to unfold the sectional front leg.

Of course, changes may be made in details of construction and operation without departing from the spirit and scope of my invention. I do not limit myself, therefore, to the exact form 10 herein shown and described other than by the appended claims.

I claim:

1. An ironing board comprising a top, rear legs, and a front leg therefor, and a foot member on said front leg bent in the direction of 15 said rear legs whereby to prevent creeping of said board in use.

2. In combination, a board and a folding supporting means therefor, comprising a leg pivoted 20 to said board adjacent one end thereof, a second leg pivoted to said board, said second leg comprising two sections pivoted together, and connecting rods between said legs whereby the same are synchronously movable to folded and unfolded 25 positions with relation to said board and said sections are simultaneously foldable about their pivot, at least one of said connecting rods being pivoted to one of said sections adjacent its point of pivot to the other section.

3. In combination, a board and a folding supporting means therefor, comprising a leg pivoted 30 to said board and adjacent one end thereof, a second leg pivoted to said board, said second leg comprising two sections pivoted together at a point intermediate the ends of one of said sections, and connecting rods between said legs whereby the same are synchronously movable to 35 folded and unfolded positions with relation to

said board and said sections are simultaneously foldable about their pivot, one of said connecting rods being pivoted to one of said sections adjacent its point of pivot to the other section.

4. In combination, a board and a folding supporting means therefor, comprising a leg pivoted 5 to said board adjacent one end thereof, a second leg pivoted to said board, said second leg comprising two sections pivoted together, said sections being of substantially the same length 10 whereby when the same are folded together about their pivot said second leg is substantially shorter than when said sections are unfolded into board supporting position, and connecting rods between 15 said legs whereby the same are synchronously movable to folded and unfolded positions with relation to said board and said sections are simultaneously foldable about their pivot, one of said connecting rods being pivoted to one of said sections adjacent its point of pivot to the other 20 section.

5. In combination, a board and a folding supporting means therefor, comprising a rear leg structure pivoted to said board adjacent one end thereof, a front leg structure pivoted to said 25 board, said front leg structure comprising two sections pivoted together, and connecting rods between said rear and front leg structures whereby the same are synchronously movable to folded and unfolded positions with relation to said 30 board and said sections of the front leg structure are simultaneously foldable about their connecting pivot, one of said connecting rods being pivoted to one of said front leg sections adjacent its point of pivot to the other section, and another 35 of said rods being pivoted to the connecting pivot of said sections.

HAROLD HOWE.
